UNITED STATES PATENT OFFICE.

LESLIE H. L'HOLLIER, OF AKRON, OHIO, ASSIGNOR TO THE B. F. GOODRICH COMPANY, OF NEW YORK, N. Y., A CORPORATION OF NEW YORK.

RUBBER BOOT.

Application filed April 21, 1925. Serial No. 24,763.

This invention relates to rubber boots of the full length or wading type and has for an object to provide a common means for securing the boot at hip-height to the belt 5 of the wearer and for holding the cuffed top in turn down position about the lower leg of the boot.

Heretofore it has been the practice to provide short straps and cooperating buckles 10 for binding the cuffed top of the boot in turned down position and a separate strap passing through a loop at the upper, outer side of the boot for holding the boot at its full-extended height or hip position. A 15 boot of this construction is subject to the objection that when worn fully extended the cuff straps frequently become loosened, catch in the brush and cause annoyance by their flapping, and when the boot is turned 20 down, the strap supporting the boot from the belt is detached from the boot and is easily lost or mislaid, this being particularly the case where boots are packed away hurriedly at the end of a trip.

25 The present invention overcomes these difficulties since it utilizes a single strap for binding the upper leg in cuffed or turned down position and for holding the boot in its extended hip position, and hence when 30 the boot is worn, it is always in service in performing one or the other of its functions. Further, the strap is designed to be always attached to the boot and therefore minimizes the possibility of its becoming separated 35 therefrom either in use or in storage.

40 Of the accompanying drawings, Fig. 1 is a side elevation of my improved boot in full extended position, the supporting strap being shown looped about the belt of the wearer; Fig. 2 is a side elevation of the boot, with the upper leg portion folded down or cuffed over the lower leg portion and the strap wound helically about the cuffed portion of the boot; and Fig. 3 is a detailed 45 view showing the attachment of the strap to the boot.

45 Referring to the drawings, the boot is formed with a foot portion 10, a lower leg portion 11 and upper leg portion 12, which 50 is relatively thin and highly flexible to facilitate the turning of the same into cuffed position, as is customary with rubber boots of the hip height or wading type.

55 The boot is provided with a strap 15 which both holds the boot in the extended

position of Fig. 1 and in the cuff position of Fig. 2. As best shown in Fig. 3, the strap 15 has secured at one end a buckle 16 and a rectangular band 17, the latter presenting a loop at the inner side of the strap. 60 The strap end is passed through a ring 18, secured to the upper leg 12 of the boot, through the band 17, and then pulled to bring the buckle end of the strap and the band 17 into a slip-noose relation to the 65 ring 18. The ring 18 is preferably fastened to the outside wall of the boot near its upper margin by means of two loops 19, 20, preferably of rubber coated fabric, the loop 19 extending vertically and embracing a lower 70 segment of the ring 18 and the loop 20 extending horizontally to embrace a forward side segment thereof, thus leaving the upper and rear segments of the ring 18 free of obstructions to permit the noosed strap 15 to 75 assume either of its operative positions. The attachment of the ends of the loops 19, 20 to the boot may be reinforced by an arcuate strip 21 of rubber coated fabric, both 80 the loops and reinforcing strip being integrally united to the upper leg of the boot by vulcanization. A buckle 22 is secured to the upper leg portion sufficiently below the ring 18 to assume a position near the lower 85 margin of the cuff when the boot is turned down to knee height. Preferably the buckle 22 is disposed rearwardly of the ring 18 so as to provide a slight overlap in the traverse of the strap around the cuffed boot leg.

90 For securing the boot in its full extended position, the end of the strap 15 is passed up under the belt of the wearer, then down and through the buckle 16, and drawn taut, the upward pull on the boot being sustained largely by the loop 19. When it is desired 95 to wear the boot at knee length, the upper leg is cuffed, the strap 15 wound helically about the boot, and its end secured in the buckle 22 (see Fig. 2), the pull of the strap on the ring 18 now being largely sustained 100 by the horizontal loop 20. When the boot is removed the strap 15 hangs loosely from the ring 18, as shown in Fig. 3, and since it is never necessary to remove it from the boot, the danger of losing or misplacing the 105 strap is obviated.

I claim:

1. A rubber boot of the wading type having a strap attached thereto and provided with means for supporting the leg of the 110

- boot at full length by attachment to the clothing of the wearer at a point above the top of the boot, and means for binding the strap about the boot when in cuffed or drawn-down position.
2. A rubber boot of the wading type having a strap provided with a buckle at one end, means for loosely fastening the buckled end of the strap to the boot leg adjacent the upper margin thereof, and a second buckle secured to the boot leg at a materially lower position than said fastening means.
3. A rubber boot of the wading type having a ring secured thereto near the upper margin thereof, a strap provided with a buckle at one end and slip-noosed at the buckle end in said ring, and a second buckle secured to the boot below and to the rear of said ring.
4. A rubber boot of the wading type hav-

ing near the upper margin thereof a ring secured thereto by means embracing the ring so as to leave a side and top portion of the ring free, and a strap device embracing the free portion of the ring and adapted to exert a direct upward pull or a direct lateral pull on said ring.

5. A rubber boot of the wading type having near the upper margin thereof a ring secured thereto by means embracing the front and bottom of the ring, leaving the rear and top of the ring free, a strap construction provided with a buckle and slidably embracing at its buckle end the free portion of said ring, and a second buckle secured to the boot at a materially lower position than said ring.

In witness whereof I have hereunto set my hand this 14th day of April, 1925.

LESLIE H. L'HOLLIER.
